UNITED STATES PATENT OFFICE.

ROBERT RUSSEL KENNEDY, OF WEST WHEELING, OHIO.

SYRUP-CONTAINER.

1,232,930.

Specification of Letters Patent. Patented July 10, 1917.

Application filed October 23, 1915. Serial No. 57,578.

To all whom it may concern:

Be it known that I, ROBERT RUSSEL KENNEDY, a citizen of the United States, residing at West Wheeling, in the county of Belmont and State of Ohio, have invented certain new and useful Improvements in Syrup-Containers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to an improved container for syrup or any liquid commodity. The object of the invention is to provide an article of the above character which is sanitary and of easy manipulation in discharging the contents from the container. A further object of the invention is to provide a device for controlling the discharge of liquid from the container which is confined wholly to the cover or lid of the container and therefore is capable of being used on a variety of containers and is not rendered useless should a particular container be destroyed or broken.

In the accompanying drawings, Figure 1 is a vertical longitudinal section of my improved container showing the discharge spout in a closed position. Fig. 2 is a similar view of the upper portion of the device showing the discharge spout open. Fig. 3 is a top plan view of the container.

In a detail description of my improved syrup container, similar reference characters indicate corresponding parts.

The jar 1 may be of any suitable design or shape as well as of any suitable material for table wear, such, for example, as glass. The mouth of said jar is provided with exterior grooves or screw-threads which are engaged by similar threads of a cap 2 which close the mouth of the jar. The cap 2 has its top rounded and is provided with an inner straight wall 3 which engages the top of the jar when the cap is screwed into position. A cylinder 4 is rigidly united to the cap and extends through both walls thereof, the ends of said cylinder extending above and below the outer and inner walls of the

cap. The cylinder 4 constitutes an inclosure for an inner cylinder or spout 13. The upper end of said cylinder is flared outwardly as at 5 in the form of a spout and is provided with a lid 6 which controls the outlet through said spout. The lid 6 is pivotally united at 8 to a finger lever 7 which in turn is pivoted at 9 to a suitable bifurcated standard 10 on the cap 2. The free end of the lever 7 is provided with a flat finger portion 11 by which it is conveniently manipulated to open the lid 6, a spring 12 being arranged to normally close said lid by exerting upward pressure on the free end of the lever. The inner cylinder 13 is mounted freely within the cylinder 4. This inner cylinder 13 is pivotally mounted at 15 to the inner side of the lid 6 and has a discharge spout 14 through which the liquid is discharged when the lid 6 and inner cylinder 13 are elevated, as in Fig. 2. The lower end of the inner cylinder 13 terminates in a flange 16 which constitutes in effect a valve in that it co-operates with the lower end of the outer cylinder or spout 5 in shutting off any passage of the liquid between the outer and inner cylinders when the device is manipulated to discharge the contents of the jar, as shown in Fig. 2.

While in the drawings I have shown the outer cylinder having its outer end formed with a spout 5, it may be desirable to omit this spout 5 and to make the cylinder of uniform diameter in the event that the container is used for liquids other than syrup. The object and purpose of the spout 5 is to catch the drippings that may drop from the inner spout 14 when syrup is being discharged from the container. It will be observed from Fig. 1 of the drawings that when the container is not in a position to discharge the contents the spout 13 is inclosed so that in the case of syrup the air is excluded from the spout and the tendency of the syrup remaining therein to solidify or turn to sugar is obviated. This is an important feature of the device as well as the protection of the spout from the accumulation of dust that would find ready adherence to the syrup in the event that the spout were exposed to the air.

Having described my invention, I claim. In a liquid container, a jar having a cap

forming a closure therefor, a cylinder rigidly secured in said cap, a discharge spout within said cylinder having its lower end open and terminating in an outwardly lying flange adapted to seal the space between said cylinder and spout when the spout is elevated, a cover forming a closure for the cylinder and to which said spout is connected, and a finger lever fulcrumed on said cap and

connected to said cover, substantially as 10 specified.

In testimony whereof I affix my signature, in presence of two witnesses.

ROBERT RUSSEL KENNEDY.
